J. F. BIRCHARD

ESCRITOIR.

UNITED STATES PATENT OFFICE.

JOHN F. BIRCHARD, OF MILWAUKEE, WISCONSIN.

DESIGN FOR AN ESCRITOIRE.

Specification forming part of Design No. 5,315, dated October 17, 1871.

To all whom it may concern:

Be it known that I, JOHN F. BIRCHARD, of Milwaukee, in the county of Milwaukee, in the State of Wisconsin, have invented a certain Design for Escritoire, of which the following is a specification:

My invention is an escritoire or writing-desk, and is constructed wide at the bottom, from front to rear, with ornamental work at the bottom, with a mirror in front hung a little below its center, so that when it is raised up to a little back of a vertical position it will fall back of itself to its place, and when pulled down forms a writing-desk, and the top of this escritoire or writing-desk is ornamented, making a very tasty and useful piece of furniture.

The nature of my design is fully represented in the accompanying photographic illustration to which reference is made, in which—

A is the body of the escritoire; B, the lower ornamental work; C, a mirror in the front of the escritoire; D, the inside work; E, the ornamental work up and down the front on each side of the mirror; F, a drawer and cover on the top of the escritoire; G, ornamental work on the top of cover F, and between that and shelf H; I, ornamental finish standing on shelf H.

What I claim as my invention is—

1. The ornamental work B, substantially in the manner above described.
2. The hanging mirror C, in combination with the ornamental work E, substantially as described.
3. The drawer F and cover on the top of the escritoire, in combination with the ornamental work G, substantially as described.
4. The shelf H, in combination with the ornamental work I, substantially as described.
5. The design of the general contour of the escritoire, substantially as described.

JOHN F. BIRCHARD.
